UNITED STATES PATENT OFFICE.

MARTIAL REDON, OF LIMOGES, FRANCE.

DESIGN FOR A CUP.

SPECIFICATION forming part of Design No. 23,280, dated May 22, 1894.

Application filed September 20, 1893. Serial No. 486,034. Term of patent 7 years.

To all whom it may concern:

Be it known that I, MARTIAL REDON, a citizen of France, residing at Limoges, in the Republic of France, have invented and produced a new and original Design for a Cup, of which the following is a specification.

The accompanying drawing is a perspective view of a cup embodying my design.

The essential features of my design are lodged in a composite arabesque leaf and shell pattern and escaloped ornamentation and a series of lines vertically arranged upon the ware substantially as shown in the drawing.

The cup is ornamented upon its bottom portion by a composite leaf-shaped arabesque and shell ornamentation which terminates irregularly in scrolls and leaf-shapes upon the side of the ware leaving a plain exterior surface. This plain surface is segmented by a series 20 of curved vertically arranged lines producing in the ware a quarterfoil ornamentation which is especially observable on the lip of the cup.

A line of escaloped ornamentation is located below the edge of the cup; the escalops are strongly accentuated on their upper edge near 25 the lip of the cup and gradually merge into and are lost in the plain exterior surface of the ware. The handle has upon it a composite arabesque ornamentation.

In the drawing A is the lip of the cup. 30

B is the handle.

C is the arabesque and shell-shaped ornamentation.

D is the segmental ornamentation.

E is the escaloped ornamentation and F is 35 the plain exterior surface.

What I claim is—

The design for a cup substantially as herein shown and described.

MARTIAL REDON.
